CLAIM

We claim the ornamental design for a housing for barrier movement controller, as shown and described.

DESCRIPTION

FIG. 1 is a perspective view of a housing for barrier movement controller;

FIG. 2 is a front elevational view of the housing for barrier movement controller of FIG. 1;

FIG. 3 is a left side elevational view of the housing for barrier movement controller of FIG. 1, a right side view is a mirror image of the left side;

FIG. 4 is a top plan view of the housing for barrier movement controller of FIG. 1, a bottom plan view is identical to the top plan view; and,

FIG. 5 is a rear elevational view of the housing for barrier movement controller of FIG. 1.
